UNITED STATES PATENT OFFICE.

NATHANIEL S. MONROE, OF ARTHUR, ILLINOIS.

DRAG.

1,291,594.

Specification of Letters Patent. Patented Jan. 14, 1919.

Application filed October 29, 1917. Serial No. 199,032.

To all whom it may concern:

Be it known that I, NATHANIEL S. MONROE, a citizen of the United States, residing at Arthur, in the county of Douglas and 5 State of Illinois, have invented certain new and useful Improvements in Drags, of which the following is a specification.

This invention relates to road drags of the general class or type shown, for instance, 10 in Letters Patent of the United States, No. 1,176,591 granted to me on March 21, 1916.

One object of the present invention is to construct a machine of the class described which will be made entirely of metal and 15 in a light and durable manner, material being economized as far as consistent with proper strength and durability.

A further object of the invention is to construct a drag of the class described which 20 may be utilized as a scraper or as a smoothing or troweling device by simple adjustment of the parts thereof, said parts being arranged and connected together in a simple and improved manner.

25 Further objects of the invention are to simplify and improve the general construction and arrangement of the detailed parts of the device.

With these and other aims in view which 30 will readily appear as the nature of the invention is better understood, the same consists in the improved construction and combination of parts which will be hereinafter fully described and particularly 35 pointed out in the claim.

In the drawings hereto annexed there has 40 been shown a simple and preferred embodiment of the invention; it being, however, understood that no limitation is necessarily made to the precise structural details 45 therein exhibited, but that changes, alterations and modifications within the scope of the appended claim may be resorted to when desired.

45 In the drawings:

Figure 1 is a perspective view of a drag constructed in accordance with the invention.

Fig. 2 is a vertical, sectional view of the 50 same.

Fig. 3 is a sectional view similar to Fig. 2, but showing the device arranged for smoothing or troweling.

Fig. 4 is a sectional detail view taken on 55 the line 4—4 in Fig. 1.

Fig. 4^a is a sectional, detail view taken on the line 4^a—4^a, in Fig. 4.

Figs. 5 and 6 are detailed views of the draft chain and the draft link.

Fig. 7 is a sectional, detailed view illustrating a modification.

Fig. 8 is a front view of a portion of Fig. 7.

Fig. 9 is a detail view illustrating a further modification. 65

Corresponding parts in the several views are denoted by like characters of reference.

In the construction of the improved machine there are included two angle bars 15, 16, of iron or steel which constitute respectively the front and rear bars of the drag.

On the vertical web of the front bar, which faces toward the front, is riveted or otherwise secured a scraper blade 17, the working edge of which extends below the horizontal web of said angle bar. Riveted or otherwise secured on the under face of the horizontal web of the rear angle bar is a troweling plate 18. The blade 17, and the plate 18, are each of a length substantially equal to the length of the angle bars. It may also be stated that while the horizontal web of the front angle bar is of sufficient width to constitute a troweling member, the rear angle bar is of relatively small 85 dimensions, the horizontal web being comparatively narrow and utilized merely for the attachment of the troweling plate 18.

The front and rear bars 15, 16, are connected together by angle bars 19, of which 90 three have been shown, one being located near each end and one about midway between the ends of the front and rear bars. The angle bars 19, are riveted or otherwise secured on the horizontal web of the rear bar 16; firmly secured on the front bar 15, are angle blocks or lugs 20, with which the vertical webs of the angle bars 19, are pivotally connected by means of bolts 21. The angle bars 19 are bent upward about mid- 100 way between their front and rear ends as seen at 22, thereby causing the forward portion of the plate 18, to be tilted upwardly as clearly seen in Figs. 1, 2 and 3 of the drawings. The pivotal connection of the front bar 15, with the angle bars 19, will permit the said front bar to be tilted to the position illustrated in Figs. 1 and 2 where the scraper blade 17, will engage the surface of the ground, and also to the position 105

110 of the ground, and also to the position 110

illustrated in Fig. 3 where the said blade is supported above the ground while the horizontal web of the angle bar 15, is in troweling engagement with the ground.

5 Firmly secured on the vertical web of the angle bar 15, is a vertically disposed angle bar 23, the same constituting an upright with which a lever 24 is firmly connected, said lever being secured by rivets 10 25, on the rearwardly extending web of said angle bar 23. Another short angle bar 26, constituting a foot piece, is secured on the laterally extending web of the angle bar 23. It is evident that by means of the lever 15 24, the front angle bar may be tilted about the axes of the bolts 21.

For the purpose of retaining the parts securely at various adjustments, various means of slightly different nature may be employed. In Fig. 2 a bar 27, has been shown, said bar being pivoted on the middle angle bar 19, and said bar extending through a slot 28, which may be formed by a keeper 29, secured on the lever, said bar 25 having notches 30, adapted for engagement with a pin 31, disposed transversely in the slot. A spring 32, has been shown whereby the notched bar is retained in engaging position, and the said bar is provided with a 30 foot piece or treadle 33, extending at an angle thereto. In Fig. 3 the spring 32, is omitted. In Fig. 7 both the spring 32 and the foot piece 33, are omitted and the keeper, here designated by 28', is provided with 35 rounded engaging faces 34, for the notched bar which, in this instance, has the notches 30' formed in the upper instead of the lower edge thereof, said notches being engaged by a latch 35, pivoted on a lug 36, extending 40 from the lever 24, as best seen in Fig. 8. In Fig. 9 a similar construction is shown except that the lug 36', on which the latch 35 is pivoted, extends from the keeper.

A seat support is provided, the same consisting of downwardly diverging legs 37, the lower ends of which are secured on the vertical web of the rear angle bar 16, a third leg 38, being connected at its upper end with the upper ends of the legs 37 and at its lower 50 end with the middle angle bar 19. The seat 39, is secured by a fastening member 40, to the upper ends of the several legs.

A draft chain 41, is terminally connected with the bolts 21, whereby the angle bars 55 19, at the two ends of the machine, are connected with the lugs 20. The draft chain extends above the upper edge of the scraper edge 17, and it carries a draft link 42, the eye or opening of which is of keyhole shape 60 so that in one position of said link, as seen

in Fig. 6, it may be moved lengthwise of the chain while in another position of said link, indicated in Fig. 5, the narrow portion of the keyhole opening may be engaged between two links of the chain, thereby retaining the draft link in adjusted position as seen in Fig. 1. It will be readily seen that by proper adjustment of the draft link, draft may be applied midway between the ends of the front bar 15, thereby causing said front 70 bar to be presented at right angles to the line of draft while, by moving the draft link toward either end, a slanting position with respect to the line of draft may be obtained.

75 It will be readily seen that when the lever 24 is disengaged from the notched latch bar, the operator, by placing his feet on the foot piece 26, and using his hands for manipulating the lever, may forcibly tilt the front 80 bar 15, of the machine to the most desirable position for operation, such position being retained by means of the notched latch bar. The latter, in the forms of the invention illustrated in Figs. 2 and 3 may be actuated 85 by the treadle 33. In the forms shown in Figs. 7, 8 and 9, the locking latch 35, is operated by hand.

The machine herein shown and described is extremely simple, strong and durable and 90 it may be manufactured and marketed at a moderate expense.

What I claim as new and desire to secure by Letters Patent is:—

In a drag of the class described, front and 95 rear angle bars, connecting bars with which the rear bar is securely connected, means whereby the front bar is pivotally connected with the connecting bars, and means for tilting the front bar, said means including 100 an upright angle bar secured to the front bar in the angle thereof, a lever secured in the angle of the upright angle bar and a horizontal angle bar secured on the upright angle bar and constituting a foot piece; in 105 combination with means for retaining the lever and the parts controlled thereby at various adjustments; said means including a pivotally supported notched bar, a keeper on the lever through which said bar extends, 110 an engaging member on the lever for the notched bar, and an arm extending from the notched bar and constituting a treadle whereby it may be actuated.

In testimony whereof I affix my signature 115 in the presence of two witnesses.

NATHANIEL S. MONROE.
